(57) **CLAIM**

I claim the ornamental design for a window vent, as shown and described.

DESCRIPTION

FIG. 1 is a perspective view of a window vent as viewed from the front, bottom and left side, according to one embodiment. FIG. 2 is a left side elevation view of the window vent of FIG. 1.

FIG. 3 is a right side elevation view of the window vent of FIG. 1.

FIG. 4 is a bottom plan view of the window vent of FIG. 1.

FIG. 5 is a top plan view of the window vent of FIG. 1.

FIG. 6 is a front elevation view of the window vent of FIG. 1.

FIG. 7 is a rear elevation view of the window vent of FIG. 1.

FIG. 8 is a perspective view of the window vent of FIG. 1 when closed, as viewed from the rear, the bottom and the left side.

FIG. 9 is a rear elevation view similar to FIG. 7, except showing the window vent in an opened position; and,

FIG. 10 is a perspective view similar to FIG. 8, except showing the window vent in the opened position.
